UNITED STATES PATENT OFFICE.

MARTIN A. MALIA, OF THOMPSONVILLE, CONNECTICUT.

DESIGN FOR A LUNCH-ROOM CHAIR.

Application filed June 17, 1922. Serial No. 2,723. Term of patent 7 years.

To all whom it may concern:

Be it known that I, MARTIN A. MALIA, a citizen of the United States of America, residing at Thompsonville, in the county of Hartford and State of Connecticut, have invented a new, original, and ornamental Design for Lunch-Room Chairs, of which the following is a specification, reference being had to the accompanying drawing, forming part thereof.

Fig. 1 is a front elevational view.
Fig. 2 is a side elevational view and
Fig. 3 is a plan view, showing my new design.

What I claim is:

The ornamental design for a lunch room chair, as shown.

MARTIN A. MALIA.
